UNITED STATES PATENT OFFICE.

PHILIP HENRY WYNNE, OF BOSTON, MASSACHUSETTS, ASSIGNOR TO
CHARLES HENRY HUFF, OF BROCKTON, MASSACHUSETTS.

METHOD OF ELECTROSTATIC SEPARATION.

No. 805,694.

Specification of Letters Patent.

Patented Nov. 28, 1905.

Application filed August 2, 1904. Serial No. 219,240.

To all whom it may concern:

Be it known that I, PHILIP HENRY WYNNE, a citizen of the United States, and a resident of Boston, in the county of Suffolk and State 5 of Massachusetts, have invented new and useful Improvements in Methods of Electrostatic Separation, of which the following is a specification.

My invention relates to the art of electrostatic separation or concentration; and it consists of a new and improved method whereby substances of different degrees of electroconductivity are separated, concentrated, or classified by the employment of static 15 charge.

My new method is characterized by the regulation and time limitation of static charge with respect to the elapsed times required for different substances to become 20 charged by static electricity.

My process is correctly defined as one of electrostatic separation, concentration, or classification, although the primary source of electricity which I prefer to employ is a 25 high-frequency alternating-current dynamo, because in its immediate application to the materials treated there is no electric current manifested, except possibly in the form of inappreciable leakage, the working terminals 30 or electrodes of the circuit employed immediately upon the material receiving a charge which is to all substantial intents and purposes a static charge which is not transferred between the said terminals in such manner 35 as to produce an electric current by conduction. Because of the rapid variation of relative potential of the electrodes there is, however, a displacement-current in the intervening dielectric.

40 The practical applications of my new process are diverse. A typical example is afforded by the separation, concentration, or classification of metallic ores and their removal from the gangue, wherewith they are more or 45 less intimately mixed.

50 Mine is a method in which the potential at the electrodes of a static separator is suddenly or abruptly raised or applied and suddenly withdrawn or lowered, the application 55 of potential enduring through a very brief interval of time, also in which these applications or variations of potential recur rapidly—that is to say, frequently—also in which the electrodes possess no potential or potential to 60 an ineffective degree in the intervals between successive applications of effective potential.

I have discovered that in processes of electrostatic separation or concentration the best results are produced by rapidly varying 60 or oscillating the potential of the electrode or electrodes employed by reducing the time during which the maximum emphatic or pronounced potential is applied to periods of extreme brevity, that it is usually preferable, 65 but not always necessary, that these intervals of pronounced potential be brief both absolutely in time and relatively also to the entire period or cycle of potential variation.

All existing processes of electrostatic separation or concentration, including that hereinafter described, are carried out by subjecting the mixture of two or more materials which it is desired to separate to the influence of a charge of static electricity. The 70 principle of operation of the class of processes to which my invention belongs is and has been to charge conductive particles in contact with an electrode while not charging the non-conductive particles. A charged 75 particle being electrically one with while mechanically separable from the electrode which defines the field responds to the convective force of the field and is conveyed 80 away, or, as prior patents have said, is "repelled" from the electrode. An uncharged particle does not become electrically one with the electrode and is not conveyed away 85 or repelled, but falls from the electrode or, it may be, clings thereto. The fundamental 90 principle of force on which all the electrostatic separators of this class heretofore known to me have operated is the mechanical convection by a static field of conductive particles which by conduction become one 95 electrically with while they are mechanically separable from an electrode in contrast to the indifferent behavior of non-conductive particles, which receive no such charge and feel no such convective influence. My in- 100

vention rests on the same fundamental principle, but is distinguished by a regulation of the static charge and its controlled application to the electrodes and to the material treated, as will hereinafter appear. Prior to 105 this my invention and my discovery of the practical economies and benefits to be derived from the use of rapidly-varied or mo-

mentarily-applied potential in electrostatic separation it has been, so far as I am informed, the aim of inventors and experimenters in the field of electrostatic separation to 5 employ a continuously-applied potential, and it was due to this fact that the resulting concentrates were necessarily impure. The unsatisfactory results were not due to insufficient potential or poor insulation of the machines; but the reason was probably to be found in the tendency of the continuously-maintained static charge to influence the less susceptible particles of the mass under treatment—as, for instance, the particles of 10 crushed rock wherewith metallic ore is mingled—either directly by contact with the electrode or by indirect communication from neighboring conducting particles, thereby causing them to mix themselves to a greater 15 or less extent with the more susceptible particles from which it was desired to separate them. It is possible also that the machine portions adjacent to the charged electrode under a continuously-applied potential retain 20 a certain portion of the charge and that the non-conducting particles tend to become charged therefrom. These prior processes had for their working hypothesis that conductors would be charged and carried over, 25 (repelled,) while non-conductors would not be charged, not be conveyed away, and would merely fall from the electrode, and in so far as examples could be found that presented materials which were actually conductors 30 and non-conductors under the electrical conditions existing the prior processes succeeded; but unfortunately very many materials acted as conductors under those conditions, and while “repulsion” took place abundantly 35 too many materials were repelled.

Whatever may be the electrical conditions to which the term “conductivity” is made to refer it can only possess a relative significance. All solid substance transmit electricity to some extent and all to a greater or 45 less degree resist the transmission of electricity. Substances which are practical insulators under some conditions become conductors under other conditions. I shall 50 herein use the word “conductivity” in a sense which is exact, as defined hereinbelow, but which involves some extension of the meaning ordinarily understood or conveyed by the word. By the conductivity of a body I 55 mean the measure of the ability of that body to assume a charge of electricity when put into effective contact with another body which is charged. This quality—conductivity—is also measured (other things being 60 equal) by the rapidity with which the body can assume a charge when put into effective contact with another charged body. This definition is necessary, because the theory of the conditions under which a body can receive 65 a charge is now undergoing consider-

able revision on account of sundry electrolytic phenomena and of phenomena associated with the effects of radium, X-rays, ultra-violet light, &c., and the effects thereof upon the electric charges carried or assumed by bodies which would ordinarily be considered to be non-conductors or insulators.

My invention, therefore, relates to bodies or particles defined or characterized simply by their ability or non-ability to receive 75 static charge by effective contact, and should not be understood in a limited sense by reason of uncertain hypotheses concerning the elementary mechanism of charge transmission. I use the term “effective contact,” because 80 in the actual operation of my process the repulsion from an electrode of a particle may be due to charge communicated to it by a short electric spark before or without absolute mechanical contact being established, 85 just as a Leyden jar may be charged by sparks without mechanical contact.

So far as I have observed in the treatment of very many substances all solid particles will if subjected long enough to contact with 90 a continuously statically charged body receive or assume the charge. Moreover, substances differ between each other in the elapsed times required to become charged under stated sustained charge. I have discovered 95 that the communication of charge may be confined to selected bodies in a mixture by limiting the duration of charge on the contact-body to a period too short to enable bodies other than those selected to receive the charge, while long enough to enable the selected bodies to receive it. Under proper mechanical conditions the selected 100 best conductors will thus be charged and repelled, whereas the poorer conductors are now 105 charged and are not repelled.

While under the conditions of continuous charge peculiar to prior processes many substances of different degrees of conductivity were repelled together, by my process such a 110 selection is made according to degrees of conductivity that under the conditions imposed all but a selected portion of the mixture treated are to all practical intents and purposes as if they were absolute non-conductors.

The practical application of this method is susceptible of variation within wide limits, and these are ascertained, so far as I am aware, by determining the combination or 120 relation of the capacity and potential, so as not to make the time during which the conductive particles are influenced long enough to enable the static charge to reach and influence the less conductive particles. I have 125 found that provided certain exceptional conditions subsist separation can be obtained under widely diverse conditions of electric supply. For instance, a current having the general characteristics of what is known as 130

the simple "sine-wave," such as is given by the ordinary alternating-current dynamo, will produce separation provided the maximum potential of the sine-wave is sufficiently high and provided that the frequency be not too low. A simple sine-wave of a frequency of sixty cycles will under exceptional conditions produce fair separation.

So many variables enter into the problem that it is, I believe, impracticable to attempt to prescribe except generally the upper and lower limits of frequency. The substances of which a mass to be treated is composed, the degree of their comminution, the rate of speed at which they pass through the effective electrode field, the distance and rate of travel of the mass of material between the point of delivery to the repelling-electrode, and the region where the separation of the particles becomes final all are factors which must enter into consideration, and with each given actual problem the best conditions—mechanical and electrical—must be worked out before the best results can be obtained. From my own experience with many variations of all these factors, I am of opinion that the frequency of the potential cycle should not be less than ten or twelve potential impulses during the time of transit of material from the point of delivery to the repelling-electrode to the region where separation is conclusively effected and that practically an absolute frequency of not less than twenty impulses per second is desirable. As to the upper limit of frequency that will under any given conditions effect economical separation it is not possible at present to assign a maximum. I have obtained good separation under conditions wherein computation indicated a frequency of many thousands per second, the exact period of cycle recurrence not being measurable without more elaborate apparatus than I have had at command.

The rapidity of recurrence of potential impulses has a mechanical significance. A conductive particle may be interfered with by accidental conditions which tend to hinder its effective contact with the electrode. Therefore, it is advisable to give each conductive particle many chances to receive a charge, and if there are many potential accessions on the electrode during the time required for the transit of a particle through the field territory, the better will be the chance of its receiving the charge at one point or another.

Various devices can be employed to produce the rapidly varied or changed potential effective in obtaining ore concentration free from crushed rock, sand, or other impurities. I can use a common commutator, the potential being generated by a static-influence machine or an electrolytic interrupter operating an induction-coil. A more practical commercial arrangement consists of a trans-

former operated by an alternating-current dynamo of proper frequency, together with certain subsidiary devices in the form of resistances, capacities, and spark-gaps, as described hereinbelow. The result to be attained by the devices employed is the production of a change of potential that is represented by a pointed or peaked wave. The rise and fall of potential should be very steep or rapid, especially in the neighborhood of the effective range, and the duration of the high potential very brief.

As has been already stated, the form of electric wave producing the desired separation may vary within wide limits, provided only the potential be sufficiently high and the variation of potential sufficiently rapid. I have shown in Figs. 1 to 7 the form of potential wave and the arrangements for producing the results aimed at.

Figure 1 illustrates diagrammatically an arrangement of circuits for producing the ordinary sine-wave; Fig. 2, a graphic representation of the sine-wave; Fig. 3, the arrangement preferred by me for producing a preferred form of wave; Fig. 4, a diagram of the wave produced by the apparatus of Fig. 3; Fig. 5, an arrangement for producing a potential-wave form suited to particular mixtures, and Figs. 6 and 7 such special wave-forms. Fig. 8 shows substantially the same electrical arrangement as Fig. 3, associated with electrodes of a preferred form.

Similar reference-numbers designate corresponding parts in all the figures.

The arrangement shown in Fig. 1, provided, as has been stated above, the potential and frequency be sufficiently high, produces a so-called "sine-wave" that will accomplish separation for some classes of material. 1 is a source of alternating current; 2, a transformer connected therewith; 3, one electrode; 4, a second electrode adjacent thereto and separated from electrode 3 by the non-conducting partition 5. When the alternating-current source is operated, a current is produced that is represented by the sine-wave, Fig. 2, in which the current, starting at zero, rises comparatively rapidly until it reaches its maximum positive potential, (represented by 6,) then falls to zero, and passes to its maximum negative potential, (represented by 7,) the cycle being repeated. This arrangement gives good results with certain ores or other mixtures of material; but there is danger that the non-conducting portions of the ore or the less conductive materials of the mixture, whatever may be their differentiated characteristics, will be submitted so long to the electric charge as to become charged and to respond to the repelling influence of the field. Better separation is produced by the arrangement shown in Fig. 3, and this for most ores or masses of mixed materials is my preferred form. In this

form of apparatus, 1 2 3 4 5 perform the same functions as the corresponding parts mentioned above. 8 is a resistance for the purpose of controlling the charge of condenser 9, 5 10 a spark-gap in series with the electrodes 3 and 4, and 11 a non-inductive resistance in parallel with the electrodes 3 and 4 and also with the condenser 9.

In Fig. 8 the source of potential 1, transformer 2, condenser 9, spark-gap 10, resistance 11 are associated, as in Fig. 3. A hopper H is arranged to deliver comminuted material to the electrode 3, wherefrom separation takes place, the more highly conductive 15 particles being thrown over the divider 5 toward electrode 4, while the less conductive material falls behind the divider on the side toward electrode 3. The result of this arrangement is to produce an electric wave 20 which may be graphically represented by Fig. 4, in which the potential rises almost instantly to its maximum positive potential 12, sinks very rapidly to zero, and after a certain time interval, relatively long as compared 25 with the interval occupied by the rapid rise and fall of potential, instantaneously attains its maximum negative potential 12^a, after which the cycle is recurrently continued. This preferred form of electric 30 wave gives an especially appropriate example of rapidly-varied and briefly-applied potential and is attained as follows: The source 1 of alternating electricity by means of the transformer 2 charges the condenser 9. 35 When the condenser 9 attains a sufficient charge, the spark-gap 10 breaks down, the electrodes 3 and 4 receive instantaneously a high potential, but are shunted through the non-inductive resistance 11, which short-circuiting swiftly lowers the potential back 40 to zero. With such an apparatus I have found good working conditions are afforded by a maximum potential of forty thousand 45 volts or upward, a condenser capacity of .006 microfarad, no resistances and inductances being introduced except those low ones incidental to the necessary wiring. The short-circuiting non-inductive resistance may be about one thousand ohms. The result 50 is a wave of potential represented by Fig. 4, in which the peaks are 12 and 12^a. This is an ideal form of wave, because the rise and fall of potential is very rapid, the electrode has not sufficient time to assume a 55 continuing charge, and the non-conductors or poor conductors of the mass receive no effective repellent impulse whatever in the short time interval. Of course the conducting particles take their charge or receive 60 their repelling impulse immediately and are thrown out, and the separation is almost perfect. The results attained by such a form of potential wave are so perfect as to make this a method of separation rather than of concentration, at which others have aimed. 65

In certain ores or analogous mixtures it is found that better results are arrived at by submitting them to a potential which, while rapidly varied, remains either always positive or always negative, such a potential 70 wave being represented in Figs. 6 and 7, in which 12 represents positive and 12^a negative potential. This form of wave is arrived at by interposing in the transformer-circuit a rectifier 13.

I do not claim the specific arrangement of circuits for producing the rapidly-varied potential wave employed and preferred by me, that being the invention of G. W. Pickard. I also desire again to call attention to 80 the fact that with the high potential and high frequency employed in this method the terms "conductors" and "non-conductors" or "poor conductors" are merely relative, meaning simply that one constituent of a 85 compound is more susceptible to electrification than another. My process of electrical separation characterized by the employment of rapidly-varied and briefly-applied potential is capable, moreover, of effecting a separation 90 of particles which differ in respects other than "electrical conductivity," as the term is ordinarily understood. For instance, particles of equal specific conductivity, but of different specific gravity, or particles which 95 differ in mechanical fineness of subdivision can be separated or classified according to these differentiating physical characteristics by my process, these differences between particles rendering them unequally responsive 100 to the repelling influence due to reception of the static charge of the electrode, and in some cases separation is effected by the heterogeneous particles being thrown to different distances, though all the particles may be repelled in greater or less degree. It is even likely that differences in such conditions as the state of the particles in relation to their moisture or hygroscopic qualities may be 105 made the basis of effectual separation by my method. I have demonstrated in actual practice that the use of rapidly-varied and briefly-applied potential permits the employment of potentials in the electrostatic field so extremely intense as to be effective in 110 differentiating particles which cannot satisfactorily be separated by any other known means. 115

The manifold possibilities of my process are illustrated by the treatment of comminuted masses in which several characteristics coexist which may serve as differentiating properties. Some particles, though specifically more highly conductive, possess greater specific gravity than poorer conductors, and the particles of specifically conductive or non-conductive material are graded according to size or differ among themselves in chemical composition or hygroscopic character. It is possible with my method to ad- 120 125 130

just the mechanical and electrical conditions, especially the latter, in respect to frequency, brevity, and abruptness of potential variation, so as to separate the light specific non-conductors by repellent impulses which have no appreciable effect upon the heavier specific conductors, almost reversing the more usual procedure. After such separation is effected the heavier particles, specific conductors, and non-conductors alike can be treated by another electrode, whereof the electrical conditions are adjusted differently from those at the first electrode, so that the specifically-conductive particles are separated by repulsion without regard to their actual size or specific gravity, the specifically non-conductors of all classes and grades being left as tailings. The heads and tailings may each be re-treated on electrodes having still other adjustment of electrical conditions, so that the specific conductors will be graded according to existing differentiations and the specific non-conductors also. With respect to the drawings which represent wave forms it is to be understood that a mathematically-exact illustration of the wave forms is not thereby attempted. These drawings show qualitatively only the character of the potential variations and suggest different forms whereby the same general results may be obtained.

What I claim is—

1. The method of electrostatic separation, which consists in subjecting a mixture to static electricity applied in potential accessions whereof the effective durations are adjusted to operate separatively on the better conductive particles of the mixture. 35

2. The method of separating commingled particles of different conductivities, which consists in subjecting them to effective contact with a body whereon a charge is produced by briefly-enduring potential accessions, whereof the durations are adjusted to communicate charge to the particles of better conductivity. 45

3. The method of separating commingled particles according to differences in their conductivities, which consists in applying there-to under conditions favorable to effective charge transmission, a static charge characterized by recurrent potential accessions, whereof the duration is adjusted to operate separatively on the better conductive particles. 55

4. The method of separating commingled particles according to their diverse conductivities which consists in subjecting them to static electricity applied in a recurrent cycle of potential periods, which periods are brief in relation to the complete cycle, and are of

effective duration to charge the better conductors, and of ineffective duration to charge inferior conductors.

5. The method of separating commingled particles according to their diverse conductivities, which consists in passing them through a static field under mechanical conditions favorable to conductive charge of the particles, the said static field produced by recurrent accessions of potential, each of brief duration adjusted to operate separatively on particles of better conductivity than others, and whereof the frequency is such that several accessions occur during the time required for a particle to complete its transit from the point of entrance into the effective field to that of departure therefrom. 75

6. The method of separating commingled particles according to their diverse conductivities, which consists in subjecting them to static electricity on an electrode, under conditions of effective contact with the electrode, the said static electricity applied in recurrent potential accessions whereof the durations are adjusted to operate separatively upon the particles of better conductivities, and maintaining relatively long time intervals of substantially no potential between the said recurrent accessions. 85

7. The method of separating commingled particles according to their diverse conductivities which consists in subjecting them to static electricity on an electrode under conditions favorable to effective contact therewith, the said static electricity applied in recurrent accessions of potential all of one sign, whose durations are adjusted to operate separatively upon the particles of better conductivities. 95

8. The method of separating particles of matter which consists in subjecting them to the convective force of a static field produced by recurrent accessions of potential adjusted to less time duration than required to convey the less conductive particles, but to sufficient time duration to convey the more conductive particles. 105

9. The method of electrostatic separation, which consists in subjecting a mass of material to a recurrent series of static electric charges, each of infinitesimal duration, the successive charges separated by relatively long time intervals, and the duration of the charges being adjusted to operate separatively on the particles of better conductivity. 110

Signed by me at Boston, Suffolk county, Massachusetts, this 9th day of June, 1904.
